[57] CLAIM

The ornamental design for a faucet handle, as shown and described.

DESCRIPTION

FIG. 1 is a top perspective view of a faucet handle showing our new design;

FIG. 2 is a top plan view thereof;

FIG. 3 is a left side elevational view thereof, the right side being a mirror image of the left side shown;

FIG. 4 is a front elevational view thereof; and

FIG. 5 is a rear elevational view thereof.

The broken line showing of a base for a faucet handle in FIGS. 1-5 is for purposes of illustration only and forms no part of the claimed design.
